Patented Apr. 20, 1920.

Inventor

John Ruoff,
M.B. Munnell,
Attorney

UNITED STATES PATENT OFFICE.

JOHN RUOFF, OF NEW ALBANY, INDIANA, ASSIGNOR TO INDIANA VENEER AND PANEL COMPANY, OF NEW ALBANY, INDIANA, A CORPORATION OF INDIANA.

CLAMPING DEVICE.

1,337,484.

Specification of Letters Patent. Patented Apr. 20, 1920.

Application filed December 29, 1919. Serial No. 348,023.

To all whom it may concern:

Be it known that I, JOHN RUOFF, a citizen of the United States, residing at New Albany, county of Floyd, and State of Indiana, have invented new and useful Improvements in Clamping Devices, of which the following is a specification.

This invention relates to devices for clamping articles that are to be glued together.

In wood working, many articles are "built up" by gluing together pieces of various dimensions, and of different qualities, in doing so it is necessary to subject the assembled pieces to pressure, to insure contact over the entire surface, and to express surplus glue. In some branches of the art, as in the construction of "rim bound round top work" it is desired to affix linear strips of valuable wood to the sides of a polygon shaped core, built up of inferior wood, the strips being applied to all sides of the polygon at the same time.

An object of this invention is the provision of means whereby in the construction of round top work as described, pressure may be exerted upon all sides of the polygon at the same time.

With the foregoing and other objects in view, the invention consists of the novel construction and arrangement of parts illustrated in the accompanying drawing, which forms a part of this specification, wherein is set forth an embodiment of the invention but it is to be understood that such changes and modifications may be resorted to as come within the scope of the appended claims.

In the drawing wherein similar reference characters designate like parts, Figure 1, is a plan view of an embodiment of the invention: Fig. 2, an end elevation of same: Fig. 3, a section on line 3-3 of Fig. 1: Fig. 4, a section on line 4-4 of Fig. 1: Fig. 5, a section on line 5-5 of Fig. 1, and Fig. 6, a plan view of a polygon shaped core with rim strips applied thereto.

The device comprises a stand —10— consisting of an I beam —11— of suitable length. Legs —12— are secured to the heads —13— of the beam at each end thereof whereby the beam is upheld with its stem —14— in a horizontal position. A pair of journal blocks —16, 17— are secured on the stem at each end of the beam and a journal —18— is positioned on the stem inter-

mediate its length in alignment with the end blocks. A shaft —19— is slidably positioned in said journals. The shaft is provided intermediate the center bearing and the ends with right and left hand screw threads —20—, 21—. A pair of head blocks —22, 23—, which operatively engage with the screws 20, 21, have lateral projections —24, 25—, which rest upon the upper edges of the heads of the beam. The blocks depend through openings —26, 27— in the stem, and plates —28, 29— secured to their under sides bear against the lower edges of the heads and hold the blocks in place and guide them in their movement. A hand wheel —30— on the end of the shaft provides means for its manipulation. The arrangement being such that by rotating the shaft, the blocks 22, 23, may be caused to approach or recede from the center of the shaft, and the shaft and the blocks may be slid as a unit in either direction. A pair of parallel arms —31—, connected at their outer ends to blocks —32— are secured to and project from each side of the beam centrally thereof. A shaft —34— is journaled in the lower portion of the blocks 32 and in a bearing —36— secured to the under side of the stem of the beam and is adapted to both rotate and slide therein. A pair of head blocks —37, 38— positioned between the arms 31— have lateral projections —39— which ride upon the upper edge thereof. Plates —40— secured to the lower ends of the blocks 37, 38, bear against the lower edges of the arms and hold the blocks in place and guide them in their movements. The shaft 34, is provided with right and left hand screw threads —35— which are in engagement with the blocks 37, 38. The arrangement being such that when the shaft is rotated, by means of a hand wheel —41— the blocks will advance or recede from the center and that at the same time they may be slid as a unit in either direction. A contact block —42— the face of which is disposed at an angle to conform to the objects to be acted upon, is fastened to each of the head blocks 22, 23.

In operation a core as —45— is placed upon the stand with its long side against the head block 37, a strip as —46— is placed against the opposite side of the core, the hand wheel 41, manipulated to advance the head block and clamp the strip lightly.

against the core. Other strips as —47—
—48—, are placed against the other angles
of the core. The hand wheel 30, manipu-
lated to cause head blocks 22, 23, to ad-
5 vance, bringing the contact blocks 42 against
the strips. If one of the strips is not prop-
erly centered, pressure on it may be re-
leased and the top shifted bodily together
with the other set of clamps, to properly
10 aline it. When the top is properly centered
an arm —49— which is pivoted on a block
32— is swung around over the core and en-
gaged under a hook —50— on the opposite
15 block 32. The arm 49, bears upon the core
and prevents any tendency it may have to
buckle under pressure. The hand wheels
are then turned to exert sufficient pressure
20 to cause the strips to seat properly. If the
point of pressure on a strip is not properly
located to close the joint, the clamp may be
released, the core shifted to change the
point of contact, without loosening the
25 other set of clamps.

Having thus described my invention so
25 that those skilled in the art pertaining
thereto can make and use the same, I claim:

1. In a device as characterized, a frame,
a shaft, right and left hand threads on said
30 shaft, heads slidably associated with said
shaft, whereby said heads may be caused
to approach or recede from each other,
the shaft being rotatably and slidably
35 mounted whereby it may be moved lon-
gitudinally together with associated heads.

2. In a device as characterized, a frame,
a pair of shafts rotatably and slidably
mounted on said frame at an angle to each
other and in different planes, right and left

hand threads on each of said shafts and 40
heads slidably associated with said frame
and operatively connected with said threads,
the arrangement being such that by rotation
of a shaft, the heads associated therewith will
approach or recede and that longitudinal 45
movement of the shaft will carry the heads
with it.

3. In a device as characterized, a stand
comprising an I beam supported with its
stem in a horizontal plane, bearings on said
50 stem, a shaft rotatably and slidably mounted
in said bearings, right and left handed
threads on said shaft, there being openings
in the stem coincident with said threads,
head blocks slidably positioned upon the 55
upper edges of the heads of the beam, said
heads depending through said openings and
operatively associated with said threads.

4. In a device as characterized, a stand
comprising an I beam supported with its
stem in a horizontal plane, bearings on said
60 stem, a shaft rotatably and slidably mounted
in said bearings, right and left handed
threads on said shaft, there being openings
in the stem coincident with said threads,
head blocks slidably positioned upon the 65
upper edges of the heads of the beam, said
heads depending through said openings and
operatively associated with said threads,
brackets attached to the heads of the beam 70
centrally thereof and extended laterally
therefrom, a shaft rotatably and slidably
mounted in said brackets, right and left
handed threads in said shaft, and head
blocks slidably positioned on the brackets 75
and operatively engaged with said threads.

JOHN RUOFF.
